UNITED STATES PATENT OFFICE.

PAUL E. CARTER, OF BRONXVILLE, NEW YORK, ASSIGNOR TO GENERAL RAILWAY SIGNAL COMPANY, OF ROCHESTER, NEW YORK.

TRAIN CONTROL.

Application filed November 21, 1923, Serial No. 676,109. Renewed May 28, 1927.

This invention relates to automatic train control systems, and more particularly to those types of systems in which a variable permissive speed may be set up at successive points along the track under caution traffic conditions.

In the provision of means to allow a train to proceed at a speed which will assure stoppage of the train before reaching the end of a block when the next block in advance is occupied, and which, at the same time, will not restrict the speed unnecessarily, it has been found expedient to employ a device driven from the wheels of the railway vehicle which gradually restricts the permissive speed the vehicle may attain without the infliction of an automatic brake application, and in which the permissive speed is dependent on the distance the vehicle has traveled since such device has been initiated. Since, however, there is a considerable variation in the length of the various blocks of commercial railroads the speed of a train is unnecessarily restricted if a single cam or speed restricting device initiated at the entrance to a block, is employed, this being especially true of long blocks.

With the above and other considerations in mind it is proposed to provide a car-carried system having two cams, the first of which, conveniently called the high cam, is adapted to restrict the speed gradually from a high to a medium value and the second cam, conveniently called the low cam, is adapted to restrict the speed from a medium to low value, and to provide means for initiating such cams by influences transmitted from the trackway to the vehicle through an intervening air gap when a train passes through a caution block, the high cam being shaped so that the permissive speed is gradually brought down to a constant medium speed limit which is enforced for a considerable distance; and the low cam being shaped to restrict the speed from said medium value to continuing speed of lower value; to provide means for restoring the high cam when it has reached its ultimate position and to provide means for restoring both the low and the high cams when the low cam has reached its ultimate position;

the influence communication means provided being such that if an impulse is received when both cams are in their restored position only the high cam is initiated and if an impulse is received and the high cam has already started to operate the low cam is initiated; and to provide trackway apparatus which transmits a single impulse to the car-carried apparatus near the entrance to a caution block and transmits two successive impulses at that point in a block where the low cam should be initiated providing caution traffic conditions of the particular block exist; so that, if the high cam has not already been initiated, possibly because the block has changed from a clear to a caution block in the meantime or because it has already been restored, the two successive impulses will start both the high and the low cam.

Other objects, purposes and characteristic features of the invention will appear as the description progresses.

In describing the invention in detail reference will be made to the accompanying drawings in which:

Fig. 1 shows diagrammatically and conventionally the trackway apparatus of one specific embodiment of the present invention;

Fig. 2 shows a fragmentary perspective view of the speed restricting apparatus forming a part of the present invention; and

Fig. 3 is a diagrammatic view of the car-carried apparatus in which some of the devices have been shown conventionally.

Trackway apparatus.

Referring particularly to Fig. 1 of the drawings, there has been illustrated the usual form of trackway comprising rails 1 divided by insulating joints 2 into blocks in the usual manner, the block I and the adjacent ends of two other blocks H and J being shown. Since the various blocks are the same like parts of each block have been assigned like reference characters with distinctive exponents. Each of the blocks is provided with the usual track battery 3, or other suitable source of energy, and with the usual track relay 4. The particular

train control system illustrated is preferably used in connection with systems employing a wayside signal, and although a color light signal, or a position light signal may be used, a semaphore signal Z has for convenience been shown conventionally without illustrating its well-known circuits and control devices.

Near the entrance to each block is provided a track element T comprising a magnetizable core 5 of general U-shape terminating in enlarged pole pieces 6 disposed a suitable distance (about two inches) above the level of the track rails and on the outside thereof. On the back yoke of the core 5, which is preferably laminated, is provided a coil 7 of usual and well-known construction. This coil under clear traffic conditions ahead is closed in a circuit of low resistance by the front contact 8 of the line relay 9, the line relay 9 being maintained energized under clear traffic conditions ahead through the front contact 10¹ of the track relay 4¹ by a suitable source of energy one terminal of which has been designated B the other terminal being connected to a common return wire C. At a point suitably distant in the block is provided another line relay 11 connected in multiple with the line relay 9 and adapted to maintain the coil 7^a and 7^b of the track elements T^a and T^b in a circuit of low resistance by reason of its front contacts 12 and 13 which are closed when the block ahead is unoccupied.

Just above the track apparatus shown in Fig. 1 has been graphically illustrated the permissive speeds enforced by the train control system shown and more clearly described hereinafter. When a train is passing through a caution block the solid line 16 illustrates the permissive speed enforced by the high cam and the dot-and-dash line 17 graphically shows the permissive speed enforced by the low cam.

45. Car-carried apparatus.

Speed restricting devices.—Referring more particularly to Fig. 2 there has been shown on the railway vehicle a governor shaft 20 which is driven by the wheels and axle of the vehicle in any suitable manner (not shown). On this shaft 20 is provided a speed responsive device G of the well-known centrifugal type including a grooved collar 21 urged upwardly by the compression spring 22 and adapted to be moved downwardly by reason of centrifugal force acting on the weights 23 in response to the rotation of shaft 20. This governor G is preferably supported in a spring mounted mechanism casing, in which is journaled a speed shaft 24 having a bifurcated arm 25 engaging opposite sides of the grooved collar 21, so that the speed shaft 24 and the speed arm 25 fastened thereto, move about

the axis of this shaft in proportion to the speed of the train. On the governor shaft 20 is provided a worm 27 which through suitable gears 28, 29 and 30 is adapted to rotate the pinion 31. This pinion 31 is pivotally supported in an arm 32 which is pivotally supported on one end and is urged upward at the other end by compression spring 33. To this arm 32 is fastened an armature 34 forming a part of the high cam starting magnet HCS, the armature being normally attracted by the core 35 magnetized by the current flowing in the coil 36, thereby holding this armature 34 in its lower position and maintaining the pinion 31 out of mesh with the gear 38 secured to the cam shaft 39. The gear 38 is provided with a mutilated portion 38¹, so that when the pinion 31 is in mesh with the gear 38 it may be initiated and turned only to a point where the pinion 31 reaches the mutilated portion.

To the cam shaft 39 is pinned a pinion 41 operatively engaging a gear sector 42 which is biased to an intermediate position by two compression coil springs 43 engaging this gear sector and suitable projecting lugs 44, so that the gear 38 is normally maintained in a position to have the mutilated portion directly opposite the pinion 31. To the cam shaft 39 is secured a cam 46. Near the cam 46 is provided a sector 47 biased in a counter clockwise direction by a spring 48. In order to cause the sector 47 to respond to the joint action of the speed arm 25 and the cam 46 the free end of the speed arm 25 is pivotally secured to a floating lever 49 having a roller 50 journaled to its free end which engages the surface of the cam 46. A link 51 has one of its ends pivotally secured to an eccentrically located pin 52 projecting from the sector 47, so that either a rotation of the speed shaft 24 due to increase in speed or a rotation of the cam shaft 39 due to progress of the vehicle causes movement of the sector 47. In other words, the sector 47 responds jointly to the speed of the vehicle as determined by the speed governor G through the speed shaft 24 and the restriction of the train with respect to the point at which the cam 46 is initiated as manifested by the cam 46 acting through gears connected to the wheels of the vehicle.

Adjacent to the sector 47 is provided an insulating block 54 to which are secured the spring contact fingers 55 which are biased out of engagement with each other. To this insulating block 54 is fastened a pedestal 56 having a T shaped operator 57 pivotally secured thereto. To one side of this operator is journaled a roller 58 engaging the sector 47, and to the other side is journaled an insulating roller 59 engaging one of the contacts 55. In practice the contacts 55 are connected in series with the circuit of a suitable normally energized brake control device, so

that excessive speed of the vehicle as compared with the permissive speed set up by the cam 46 causes an automatic brake application.

5 *Other car-carried devices.*—On the railway vehicle are located a number of devices which are connected together to constitute the car-carried systems, one of these devices comprises a suitable influence communicating 10 car element L, which consists of a core 62 preferably laminated and of general inverted U-shape terminating in enlarged pole pieces 63 and mounted on the vehicle so that the core 62 is adapted to inductively cooperate 15 with the core 5 of the track elements T, T^a and T^b and thereby receive impulses from such track elements. On the legs of the core 62 are provided a primary coil P and a secondary coil S, respectively.

20 The car-carried apparatus also includes a control relay CR and a repeater relay RR, these relays are preferably of the tractive armature type in which the armature is pivotally secured about a vertical axis in a 25 manner so that this axis passes through the center of gravity of the armature thereby causing the armature to be balanced and not subject to jars or vibrations. These relays are preferably mounted in a heavy casting 30 which is spring supported, so as to protect them from jars and vibrations as well as from detrimental gases, moisture and unfavorable weather conditions.

Another element of the car-carried apparatus comprises a suitable brake control device which has been conventionally illustrated by an electrically operated valve EPV. This brake control device EPV may take any one 35 of various forms, that is, may apply the brakes by actuating the usual engineer's brake valve in a manner so that the engineer cannot prevent its operation, may vent the brake pipe directly or may control a suitable brake applying device which vents the brake pipe to a predetermined extent only, and for 40 convenience has been shown in a conventional manner.

In the car-carried circuit arrangement illustrated in Fig. 3 are provided two speed 45 restricting devices such as shown in Fig. 2, and for convenience like parts of the low speed restricting devices are designated by like reference characters of the high speed restricting device with distinctive exponents L.

The speed restricting device for operating the high cam as shown in Fig. 3 is provided with additional distance cams which have not been shown in Fig. 2. Two of these 50 distance cams 65 and 66 are adapted to operate normally open contacts 67 and 68, whereas the distance cam 69 is adapted to operate normally closed contacts 70 for purposes more clearly described in the operation 55 of the system. These contacts are operated

by rollers engaging the periphery of the cams, as shown and need no further description. The low cam speed restricting apparatus is provided with a distance cam 72 adapted to operate normally closed contacts 73, 74 and 71 adapted to operate normally open contacts 75, 76 and 77.

Operation.

Normal clear conditions of the car-carried apparatus.—Under normally clear traffic conditions of the car-carried apparatus, as would be the case if the car were passing through a clear block, the primary coil P of the car element L is energized by a circuit beginning at the terminal B of a suitable source of energy having its other terminal connected to a common return wire C, and including the contacts 55 of the high cam speed restricting apparatus the contacts 55^L of the low cam speed restricting apparatus and the brake control device EPV in series, the flow of current in this circuit causes an appreciable magneto-motive-force to be set up in the car element L for reasons hereinafter given. The speed distance contact 55^L of the low cam speed restricting device is normally shunted by the contacts 73, as shown. The control relay CR and the secondary coil S are connected in series and are normally energized through a circuit which may be traced as follows:—beginning at the terminal B of a suitable source of energy, wire 78, front contact 79, of the control relay CR, wires 80 and 81, winding of the control relay CR, wire 82, secondary coil S back to the common return wire C. The current flowing in this circuit and the secondary coil S is very small and does not materially change the magnetization of the car element, it being just sufficient to maintain the relay CR energized. With this control relay CR energized the repeater relay RR is energized by a circuit readily traced in the drawing. With the repeater relay RR energized a circuit may be traced for the high cam starting magnet HCS comprising wire 83, front contact 84 of the repeater relay RR, wire 85, winding 36 of the cam starting magnet HCS, wire 86, stick contact 87 of said magnet, back to the common return wire C; and another and similar circuit may be traced through the winding 36^L of the low cam starting magnet LCS including the wires 88, 89 and 90 and the stick contact 87^L of this low cam starting magnet LCS. Another circuit may be traced for energizing the winding 36^L of the low cam starting magnet LCS as follows:—beginning at the terminal B of a suitable source of energy, wire 91, contact 70, wires 92 and 89, winding 36^L of the cam starting magnet LCS, wire 90 and stick contact 87^L, so that the low cam starting magnet LCS is energized independent of the

circuit including the front contact 84 of the repeater relay RR.

Passing through caution block.—Let us assume that a railway vehicle is moving from left to right in the normal direction of traffic as indicated by the arrow in Fig. 1 at a speed of, say, a little less than 60 miles per hour in the block H, when the second block ahead, namely the block J, is occupied by another train, it being assumed that the block I is unoccupied by another train, for otherwise the train would have already been restricted in the block H. With the block J ahead occupied by another train the track relay 4¹ assumes its deenergized position thereby deenergizing the line relays 9 and 11 and putting the coils 7, 7^a and 7^b of the track elements in an open circuit. As the train in question enters the block I the car element L comes into communicating relation with the track element T. Since, as heretofore explained, the car element L has its primary coil energized, a strong field of flux radiates from the leg carrying this primary coil. This flux ordinarily passes, to a large extent, through leakage paths back to the upper part of this leg, part of the flux of course passing through the secondary coil S.

As the car element L passes over the track element T the magnetic circuit including the core 62, is momentarily shunted, so to speak, by the core of the track element T, so that a sudden increase in flux through the secondary coil S takes place. This sudden increase of flux, it is believed, is partially due to a diversion of flux from leakage paths, as just explained, and is partially due to an increase in the total flux passing through the primary coil P. As the car element L recedes from the track element T, the flux through the secondary coil S again changes back to normal, so that a rapid increase and then a decrease of flux through the secondary coil takes place. This rapid increase and decrease of flux through the secondary coil S, by well-known principles of induction, causes a varying voltage to be induced in this secondary coil S which voltage corresponds to a single cycle of alternating current electro-motive-force. The winding of the coil S is connected to the control relay CR in a manner, so that, the first wave of this cycle of alternating current voltage opposes the voltage supplied by the battery having a terminal B which energizes the control relay CR, whereby the current flowing in the control relay CR is reduced to an extent to momentarily deenergize this relay. With the relay once deenergized the front contact 79 of this relay CR is opened and its energizing circuit permanently interrupted, so that this relay remains deenergized until it is again picked up, by some other means. Deenergization of this relay CR causes deenergization of the repeater re-

lay RR and consequently deenergization of the high cam starting magnet HCS. With the high cam starting magnet HCS deenergized the spring 33 moves the pinion 31 into engagement with the gear 38 thereby causing rotation of the cam shaft 39. After a slight amount of rotation of this shaft 39 the contacts 68 are closed, thereby again picking up the control relay CR. This control relay CR again picks up the repeater relay RR which closes its front contact 84 but does not again energize the high cam starting magnet HCS because the stick contact 87 of this magnet is open.

As the vehicle proceeds through the block I the cam 46 is gradually rotated, thereby moving the floating lever 49 in a direction to move the sector 47 clockwise. If the speed of the vehicle is not reduced in like manner so that the lower end of the arm 25 moves to the right to the same extent that roller 50 moves to the left the contacts 55 will be opened and the brakes applied, consequently the engineer must gradually reduce the speed of the train as restricted by the cam 46 to avoid an automatic brake application. The cam 46 may be cut to restrict the speed in any desired manner, the graph 16 in Fig. 1 illustrating the speed restriction inflicted by the particular cam 46 shown.

As the train reaches the track element T^a, this element being in its open circuited effective condition, the control relay CR having again been picked up, causes the transmission of a similar impulse thereby again deenergizing the control relay CR and in turn the repeater relay RR. The deenergization of the repeater relay RR, in this case, deenergizes the low cam starting magnet, because the contact 70 operated by the distance cam 69 of the high cam shaft is open. The control relay CR will now remain deenergized until restored in a manner to be described later. With the low cam initiated by the track element T^a the speed of the train is restricted from the medium to successive lower speeds until finally the minimum speed of 15 miles per hour is reached, the low speed-distance contact being made effective by the opening of contacts 73 after a short distance of movement of the train after the low speed restricting mechanism has been initiated. Also, after a short distance of movement of the train after the low speed restricting mechanism has been initiated the cam 71 completes a pick-up circuit for the control relay which may be traced as follows:—beginning at the terminal B of the battery, contacts 77, wires 94, 95 and 81, winding of the control relay CR, wire 82, secondary coil S, back to the common return wire C. The completion of this pick up circuit causes the control relay CR to again be picked up and maintained up by its stick circuit.

After the train has moved, restricted to at least a medium speed limit of 40 miles per hour, a distance as indicated by the horizontal portion of the line 16 in Fig. 1, the 5 distance cam 65 completes a pick up circuit for the high cam starting magnet HCS which may be traced as follows:—beginning at terminal B of the battery, wire 83, front contact 84 of the repeater relay RR, wire 85, 10 winding 36 of the high cam starting magnet HCS, wires 86 and 96, contact 67 back to the common return wire C, so that the high cam is again restored to its normal position by reason of the retaining gear sector 42 and 15 the springs 43.

The low cam continues to restrict the speed of the train as shown by the dot-and-dash line 17, (see Fig. 1). As the low cam has reached a predetermined position the distance cam 74 completes a pick up circuit for the low cam starting magnet LCS which may be traced as follows:—beginning at the terminal B of the battery, wire 83, front contact 84 of the repeater relay RR, wires 88 and 20 89, winding 36^L of the low cam starting magnet LCS, wires 90 and 97, contact 75, back to the common return wire C.

In applying the apparatus described to a very short block it may well happen that the 25 low cam reaches its ultimate position before the high cam reaches its ultimate position, and in order to restore the high cam at least as soon as the low cam is restored additional contacts 76 adapted to be closed by the distance cam 74 have been provided. These 30 contacts 76 are adapted to pick up the high cam starting magnet by completing the following circuit:—beginning at the terminal B of the battery, wire 83, front contact of the repeater relay RR (this relay being energized for reasons heretofore given), wire 85, winding 36 of the high cam starting magnet HCS, wires 86, 96 and 98, contacts 76, back to the common return wire C. In the particular arrangement shown and described it 35 is contemplated to effect restoration of the low cam a short distance of travel after this low cam has reached its minimum speed position, as is indicated by the dot-and-dash line 17 in Fig. 1. As shown in Fig. 1 a longer distance of travel of the train is required to operate the high cam to the position in which it restores itself (the distance from track element T to the vertical portion 40 of solid line 16, Fig. 1) than the distance of travel required to restore the low cam (the distance from track element T^a to the vertical portion of dot-and-dash line 17). This difference in the run-down distances 45 may be obtained by using different gear ratios for driving these two cams from the same shaft or the distance cams 71, 72 and 74 may be shaped to obtain the desired result with the same gear ratios. It is thus apparent that the speed restriction is released 50

at the end of the caution block by reason of the self restoring characteristics of speed restricting mechanism.

In the particular block I illustrated the restrictions enforced by the two speed restricting devices overlap each other as shown by curves 16 and 17 in Fig. 1. This is however not essential, for instance, in a short block they may be started at practically the same point, the track elements T^a and T^b 55 starting both cams which will both be restored when the low speed restricting mechanism reaches its ultimate position by the action of contacts 75 and 76 closed by the cam 74. Also, the low speed restricting mechanism may be initiated at the entrance to a caution block by placing two track elements at such point spaced substantially the same as the elements T^a and T^b. In other words the track elements T, T^a and T^b will be 60 placed at points depending on the length of the block, the grade, the condition of the trackway, and the like, so that the train in each event will be brought to a predetermined low speed or to a stop before reaching 65 the end of a caution block. Since the starting of the second or low cam depends on the condition of the first or high cam, this high cam may be considered to be a conditioning means determining the starting of the low 70 cam even though this high cam accomplishes other and additional functions.

When passing through a clear block.—Let us assume now that the train in question is approaching the block I from the left under clear traffic conditions ahead, that is, with the track relay 4 and the line relays 9 and 11 energized. As the train approaches the track element T and the car element L comes into communicating relation with this track element no impulse is transmitted to the control relay CR to deenergize this relay. One theory by which this failure of response may be accounted for, is that the passage of a small number of magnetic lines 100 through the track element T causes a current to flow in the coil 7 by induction, which coil is now closed in a circuit of low resistance, thereby causing this current to set up a counter magneto-motive-force which opposes 105 a further change of flux, all in accordance with the well-known principle of induction of alternating currents. In other words, the coil 7 when closed in a circuit of low resistance acts as a bucking coil and prevents the 110 passage of flux through the track element T, so that this track element does not have the characteristics of a piece of magnetic material, especially to the car element as it passes thereby very quickly. Since very little, if 115 any, change of flux takes place through the secondary coil S insufficient voltage is induced in this coil to oppose the battery and deenergize the relay CR so that this relay 120 CR is maintained energized and the car-car- 125 130

ried apparatus remains unchanged in passing over the track element T.

The function of the car-carried and trackway apparatus when the car element L passes by the track elements T^a and T^b with these track elements in their clear traffic condition, as shown, is exactly the same as that which occurs when passing the track element T, so that further description of the operation is unnecessary.

Having shown and described one specific embodiment of the present invention, it should be understood that the specific features shown and described have been chosen for the purpose of illustrating the nature of the invention rather than its scope, and it is desired to be understood that various changes, additions and modifications may be made to adapt the invention to the various railway systems encountered in practice without departing from the scope of the invention and the idea of means underlying the same.

What is desired to be secured by Letters 25 Patent of the United States is:—

1. An automatic train control system employing speed restricting devices of the cyclic type comprising, two separate cyclic speed restricting devices on a railway vehicle, normally energized means for maintaining said devices in their normal inactive condition, influence receiving means for deenergizing said last mentioned means upon the reception of a control influence from the trackway, means governed by one of said speed restricting devices and active only when it is in its normal condition for independently maintaining the other device in its inactive condition, and traffic controlled means located at points along the trackway 40 for transmitting control influences to said influence receiving means under danger traffic conditions ahead.

2. An automatic train control system employing speed restricting devices of the cyclic type comprising, two separate cyclic speed restricting devices on a railway vehicle, normally energized means for maintaining said devices in their normal inactive condition, influence receiving means for deenergizing said last mentioned means upon the reception of a control influence from the trackway, means governed by one of said speed restricting devices and effective only when it is in its normal condition to prevent the other speed restricting device from being initiated, whereby one of said devices is initiated upon the reception of the first influence from the trackway and the other device is initiated upon the reception of a second influence, and trackway means located along the trackway to transmit influences to said influence receiving means.

3. An automatic train control system employing speed restricting devices of the cyclic

type comprising, two separate cyclic speed restricting devices on a railway vehicle, normally energized means for maintaining said devices in their normal inactive condition, influence receiving means for deenergizing said last mentioned means upon the reception of a control influence from the trackway, means active if one of said devices is in its inactive condition for preventing the other device from being initiated upon the 75 reception of a control influence, means associated with each of said devices for restoring itself to its normal condition effective when such device has reached its ultimate condition, and trackway means located at successive points along the trackway to transmit control influences to said car-carried influence receiving means.

4. Car-carried apparatus for automatic train control systems comprising, two separate speed restricting devices of the type which if initiated are operated in accordance with the progress of the vehicle along the trackway and which enforce successive lower speed limits until they reach an ultimate position, means associated with one of said devices for restoring itself when it has reached its ultimate position, and means associated with the other device for restoring both of said devices to their normal position effective when said other device reaches its ultimate position.

5. Car-carried apparatus for automatic train control systems comprising, two distinct speed restricting devices each including a permissive speed device normally held in its maximum speed position by a normally energized electro-responsive device energized through a stick circuit which if deenergized permits said device to gradually assume more restrictive permissive speed positions, influence receiving means adapted to momentarily open both of said stick circuits upon the reception of a control influence from the trackway, means for independently maintaining the stick circuit of one of said electro-responsive devices intact effective if the other speed device is in its normal condition, and means for restoring said permissive speed devices to normal.

6. Car-carried apparatus for automatic train control systems comprising, two distinct speed restricting devices each including a permissive speed device normally held in its maximum speed position by a normally energized electro-responsive device energized through a stick circuit which if deenergized permits said device to gradually assume more restrictive permissive speed positions, influence receiving means adapted to momentarily open both of said stick circuits upon the reception of a control influence from the trackway, means governed by one of said permissive speed devices and active when this device is in its normal position to independ-

ently maintain the stick circuit of the electro-responsive device of the other permissive speed device intact, and means associated with said other permissive speed device for restoring both of said devices to normal when said other permissive speed device has reached its ultimate position.

7. In an automatic train control system, the combination of car-carried inductive influence receiving means adapted to receive momentary impulses from suitable trackway elements through an intervening air gap, a permissive speed device normally held in its inactive position which if initiated assumes more restrictive speed positions in accordance with the progress of the vehicle, means initiated in response to the reception of two successive control influences spaced apart a time allowing the vehicle to travel a certain distance and trackway devices for transmitting inductive control influences to said car-carried receiving means spaced a corresponding distance apart along the trackway.

8. Car-carried apparatus for automatic train control systems comprising, an influence receiving element having a primary exciting coil and a secondary coil thereon, a control relay connected to said secondary coil, whereby the control relay will momentarily respond when said car element passes over an active track element comprising an inert mass of iron, and means including a driving connection from the wheels of the vehicle for reducing the speed which the vehicle may attain without incurring an automatic brake application when placed in its active condition and adapted to be initiated only by the reception of two successive control influences by said control relay spaced apart at least a time corresponding to the time necessary for the vehicle to travel a predetermined distance along the trackway.

9. Car-carried apparatus for automatic train control systems comprising, a permissive speed device, an actual speed device, means for receiving momentary control influences from the trackway inductively through an intervening air gap, and means for causing said permissive speed device to inflict a more restrictive speed limit, said last mentioned means being effective only if one control influence is received a predetermined distance of movement of the vehicle before another influence is received from the trackway.

10. Car-carried apparatus for automatic train control systems comprising; a train control mechanism; and means for initiating said mechanism including a car-carried influence receiving device and a plurality of influence transmitting devices each of which when in its active condition is capable of transmitting a control influence to said car-carried device through an intervening air-gap, and including means effective only if

one control influence is received more than a predetermined distance of travel of the vehicle before another control influence is received.

11. Car-carried apparatus for automatic train control systems comprising; a train control mechanism; and means for initiating said mechanism including a car-carried influence receiving device and a plurality of influence transmitting devices each of which when in its active condition is capable of transmitting a control influence to said car-carried device through an intervening air-gap, and including means effective only if one control influence is received more than a predetermined distance of travel of the vehicle before another control influence is received provided the said another control influence is not received more than another predetermined distance of travel after the first control influence is received.

12. In an automatic train control system the combination of train control mechanism, influence communicating means partly on the vehicle and partly along the trackway for intermittently transmitting control influences from the trackway to the vehicle through an intervening air-gap, and means for initiating said train control mechanism effective only if two control influences are transmitted during the time that the vehicle travels more than a certain fixed distance and travels less than another fixed distance.

13. Car-carried apparatus for automatic train control systems comprising, normally energized and inactive train control mechanism, two circuits for energizing said mechanism, means for opening one of said circuits effective if a control influence is received and for opening the other circuit effective only after the vehicle has traveled a predetermined distance after the reception of such control influences and thereafter a second control influence is received.

14. Car-carried apparatus for automatic train control systems comprising; normally inactive and normally energized train control mechanism, two stick circuits for rendering said mechanism inactive; means for breaking one of these circuits upon the reception of a control influence transmitted from the trackway, and for breaking the other circuit upon the reception of a second control influence from the trackway providing the car has traveled more than a predetermined distance since the reception of the previous control influence.

15. Car-carried apparatus for automatic train control systems comprising; normally inactive and normally energized train control mechanism, two stick circuits for said mechanism; means for breaking one of these circuits upon the reception of a control influence transmitted from the trackway, and

for breaking the other circuit upon the reception of a second control influence from the trackway providing the car has traveled more than a predetermined distance since the reception of the previous control influence and further providing the car has not traveled more than another predetermined distance since the reception of such previous control influence.

16. Car-carried apparatus for automatic train control systems comprising, train control mechanism, a normally energized stick relay, a conditioning device which when in its active condition permits said train control mechanism to be operated by dropping of said stick relay and which is rendered active after said stick relay has been de-energized, influence receiving means for de-energizing said stick relay, means operated in accordance with the progress of the vehicle for picking up said stick relay, whereby said train control mechanism is operated if a second control influence is received and the two successive control influences are received spaced apart a time permitting the train to travel a predetermined distance.

17. Car-carried apparatus for automatic train control systems comprising, train control mechanism, a control relay, a conditioning device controlled by said control relay

effective only if the train has traveled a predetermined distance after said control relay has been operated and which conditioning device if effective permits said train control device to be operated by said control relay, and influence receiving means for operating said control relay in response to magnetic control influences transmitted by suitable trackway apparatus, whereby said train control mechanism is operated if two successive control influences are received spaced apart more than a predetermined distance of travel of the train.

18. Car-carried apparatus for automatic train control systems comprising, train control mechanism which if rendered active gradually restricts the speed of the vehicle in accordance with its progress along the track, a conditioning device, a control relay, influence receiving means responsive to a magnetic field of a trackway device for actuating said control relay, said control relay if actuated rendering said conditioning means active after a time and said control relay if actuated while said conditioning means is active rendering said train control mechanism active.

In testimony whereof I hereby affix my signature.

PAUL E. CARTER.
